BRUSH

Melvin H. Partridge, Frederick, Md., assignor to Ox Fibre Brush Company, Inc., Frederick, Md.

Application December 26, 1950, Serial No. 13,591

Term of patent 14 years

(Cl. D9—2)

To all whom it may concern:

Be it known that I, Melvin H. Partridge, a citizen of the United States of America, residing at Frederick, county of Frederick, and State of Maryland, have invented a new, original, and ornamental Design for a Brush, of which the following is a specification, reference being had to the accompanying drawing, forming a part thereof wherein:

Figure 4 is a sectional view taken on the plan indicated by the line 4—4 of Figure 2, looking in the direction indicated by the arrows, and

I claim:

The ornamental design for a brush, as shown.
